TYPEWRITING MACHINE

Jesse A. B. Smith, Stamford, Conn., assignor to
Underwood Elliott Fisher Company, New York,
N. Y., a corporation of Delaware

Application October 8, 1936, Serial No. 104,566

11 Claims. (Cl. 197—186)

This invention relates to typewriters, and more particularly to masks for portable typewriters.

The improved mask has a single one-piece cover to overlie both ribbon spools and a top plate projecting forwardly between the sides of the mask, and affording clearance for the type-bars, and conducing to ornamental appearance.

Brackets are slidably mounted on the side walls of the mask, and fixed to the side walls of the cover, and are so constructed that the cover may be moved forward to expose the ribbon spools, and also the type-bars, for inspection and cleaning.

The top cover of the mask does not interfere with movement of the carriage, even when drawn forwardly to permit ribbon changes, and type cleaning or adjustment.

The forward extension of the cover projects beyond its sides, in the same plane as the sloping front section of the sides of the mask, affording clearance for the type-bars and improving the appearance. It will not interfere with carriage manipulation either in operating or cleaning positions.

Other features and advantages will herein-after appear.

In the accompanying drawing,

Figure 1 is a perspective view looking down on an Underwood portable typewriter towards the upper front left hand corner of the machine, and showing parts of the ribbon spool cover and parts of the mask broken away.

Figure 2 is an inside side elevation, partly in section, and showing the ribbon spool cover or top of the mask in the open position; and

Figure 3 is a front view partly in section of one end of the mask, and showing the ribbon spool cover operating mechanism.

In the Underwood portable typewriter shown in the drawing, a protecting ornamental mask 10 comprises a lower portion which encases a frame 11, which is supported on legs 12. Inwardly-turned flanges 13 on the bottom of the mask 10 underlie inwardly-turned lugs 14 on the frame 11, to which they are tied by screws 15 which are surrounded by felt vibration killers 16. The mask 10 and frame 11 are further tied together in any conventional manner, which forms no part of the invention. The side wall of mask 10 has a concave portion 17 in the upper edge of the wall for the passage of the carriage of the typewriting machine. Typewriter parts, conventional with Underwood portable machines, are shown as follows: a comb type-bar guide 18, 55 keys 19, type-bars 21, a segment 22, a type-bar

guide 23, a ribbon 24, ribbon spools 25, a line-space lever 26, a reciprocating carriage 27, and a platen 28. The carriage 27 is mounted in any well-known manner and has pivotally fastened thereon the line-space lever 26 by means of a 5 screw 29.

The novel top or one-piece ribbon spool cover 30 of the mask 10 has a central cut out portion 31 in the top and ribbon-spool-clearing portions 32 laterally extended from the rear ends of sides 10 33 of said cover 30. In front a downwardly inclined section 34 extends the full width of the mask 10, said section 34 ending in a narrower section 35 to extend across and between the side walls of mask 10. A front cross-bar 36 is locked 15 by screws 37 in inclined inturned lugs 39 of the frame 11 which also supports the mask 10 by means of angle pieces 38 secured to the side walls of mask 10. A double slide bracket 40, having two upward and outwardly extending arms 20 41 is fastened by rivets 42, or other means, to the side wall portions 32 and 33 of the cover 30, and slidably mounted by means of screws 43 through slots 44 to spacers 45 and 46 secured to the side walls of mask 10. The lower slide 25 section 47 of bracket 40 is positioned between mask 10 and frame 11 and is connected to the upper section 48 by means of a vertical section 49, which has a bend 50 to enable the upper slide section 48 to extend inward over frame 11 30 in order to clear the front edge of the side wall of mask 10 when the ribbon spool cover is moved forward. Spring retaining brackets 51 are provided, mounted on both side walls of mask 10 35 for maintaining the cover 30 in its closed position, as shown by Figure 1, and in Figure 2 by dot-and-dash lines.

Variations may be resorted to within the scope of the invention, and portions of the improvements may be used without others.

Having thus described my invention, I claim:

1. In a typewriter, in combination, a frame, a platen-carriage mounted thereon, ribbon-spools mounted in front of the platen, and a mask supported on said frame, and comprising a lower portion that encases the sides and front portion of the frame, a top covering the ribbon-spools and having downwardly-extending sides that are substantially superposed on the sides of the lower mask-portion, and brackets attached to said 45 sides of the top and slidably engaged with the inner side-walls of the lower mask-portion so that said top is slidable forwardly to uncover said spools, and the top, in its forward position, is 50 clear of said carriage.

2. In a typewriter, in combination, a frame, a platen-carriage mounted thereon, ribbon-spools mounted in front of the platen, a system of type-bars, and a mask supported on said frame and comprising a lower portion that encases the sides and front of the frame, a top covering the ribbon-spools, and cut away in the central portion to clear the type-bars, said top having downwardly-extending sides corresponding with the 10 sides of the lower mask-portion, a forwardly and downwardly slanting extension from said top, co-operating with the lower mask-portion to mask the front of said frame, and means slidably supporting said top for forward ribbon-spool-uncovering displacement of the top.
3. In a portable typewriting machine, having an array of type-bars and ribbon-spools, the combination with a main frame, of a mask enclosing the same and having a single one-piece cover to overlie and mask the ribbon-spools and the type-bar array, cover-supporting floats confined within the opposite side-walls of the mask, and supports upon said side-walls whereon said floats may slide for moving the cover forwardly to expose the spools and the type-bars.
4. In a portable typewriting machine, having an array of type-bars, and ribbon-spools, the combination with a main frame, of a mask enclosing the same and having a single one-piece cover to overlie and mask the ribbon-spools and the type-bar array, cover-supporting floats confined within the opposite side-walls of the mask, and supports upon said side-walls whereon said floats may slide for moving the cover forwardly to expose the spools and the type-bars; said floats, in the form of brackets extending down from the opposite sides of the cover and having forwardly and rearwardly extending guide-slots, and said supports in the form of studs provided upon the interior of the mask and fitting said guide-slots.
5. In a portable typewriting machine, having an array of type-bars and ribbon-spools, the combination with a main frame, of a mask enclosing the same and having a single one-piece cover to overlie and mask the ribbon-spools and the type-bar array, cover-supporting floats confined within opposite walls of the mask, and supports upon said walls whereon the floats may slide for moving the cover forwardly to expose the spools and the type-bars; said floats being normally wholly within the lower portion of the mask and concealed thereby.
6. In a portable typewriting machine, having a platen-carriage, an array of upwardly and rearwardly swinging type-bars, and ribbon-spools, the combination with a main frame, of a mask enclosing the same and having a single one-piece cover to overlie and mask the ribbon-spools and the type-bar array, cover-supporting floats confined within the opposite side-walls of the mask, and supports upon said side-walls whereon the floats may slide for moving the cover forwardly to expose the spools and the type-bars; said cover formed to afford, in its closed position, clearance for the swinging type-bars, and to permit travel of the carriage whether the cover is closed or open.
7. In a portable typewriting machine, having an array of type-bars individually movable to and from a common printing point, and ribbon-spools, the combination with a main frame, of a mask enclosing the same and having a single one-piece cover to overlie and mask the ribbon-spools and the type-bar array, cover-supporting

floats confined within the opposite side-walls of the mask, and supports upon said side-walls whereon the floats may slide for moving the cover forwardly to expose the spools and the type-bars; said mask-cover having a central 5 cut-out portion for affording clearance to the moving type-bars, and also having side-portions extending outwardly relatively to said side-walls to form housings for the spools.

8. In a portable typewriting machine, having 10 a keyboard, an array of type-bars individually movable to and from a common printing point, and ribbon-spools, the combination with a main frame, of a mask enclosing the same and having a single one-piece cover to overlie and mask the 15 ribbon-spools and the type-bar array, cover-supporting floats confined within the opposite side-walls of the mask, and supports upon said side-walls whereon the floats may slide for moving the cover forwardly to expose the spools and the type-bars; said mask-cover having a centrally cut-out top-portion for affording clearance to the moving type-bars, and having side-portions extending outwardly relatively to said side-walls to form housings for the spools and also having at its front a downwardly and forwardly inclined section extending the full width of the mask; said mask having a transverse plate co-operating with said inclined cover-portion, to serve as a front plate of the mask back of the 20 keyboard.

9. In a portable typewriting machine, having an array of type-bars, and ribbon-spools, the combination with a main frame, of a mask enclosing the same and having a single one-piece 35 cover to overlie and mask the ribbon-spools and the type-bar array, floats confined within the opposite side-walls of the mask, and supports upon said side-walls whereon the floats may slide for moving the cover forwardly to expose 40 the spools and the type-bars, each float being in the form of a double-slide bracket having two slide slots, and two upwardly and outwardly extending arms fastened to the side-walls of the cover, said brackets being slidably mounted by means of screws passing through said slots in the bracket to spacers secured on the inner side-walls of the mask, said screws and spacers constituting said supports.

10. In a portable typewriting machine, having an array of type-bars and ribbon-spools, the combination with a main frame, of a mask enclosing the same and having a single one-piece cover to overlie and mask the ribbon-spools and the type-bar array, cover-supporting floats confined within opposite walls of the mask, and supports upon said walls whereon the floats may slide for moving the cover forwardly to expose the spools and the type-bars, each float being in the form of a double-slide bracket having two, upper and lower, slide slots, and two upwardly and outwardly extending arms fastened to the side-walls of the cover and slidably mounted by means of screws passing through slots in the bracket to spacers secured on the inner side-walls of the mask, said screws and spacers constituting said supports, the lower slide section of the bracket being positioned between the mask and the frame, and being connected to the upper slide section by means of a vertical section which has a bend to offset the upper slide section laterally and inwardly over the frame in order to clear the side-wall of the mask when the cover is moved forward.

5 11. In a portable typewriting machine, having an array of type-bars, and ribbon-spools, the combination with a main frame, of a mask enclosing the same and having a single one-piece cover to overlie and mask the ribbon-spools and the type-bar array, cover-supporting floats confined within opposite walls of the mask, supports

upon said walls whereon the floats may slide for moving the cover forwardly to expose the spools and the type-bars, and spring retaining brackets mounted on both sides of the mask for maintaining the cover in its closed position.
